C. DAVIDOFF

WATCH

Filed April 5, 1923

INVENTOR
Charles Davidoff
BY Mark & Stein
ATTORNEY

UNITED STATES PATENT OFFICE.

CHARLES DAVIDOFF, OF BROOKLYN, NEW YORK.

WATCH.

Application filed April 5, 1923. Serial No. 830,030.

To all whom it may concern:

Be it known that I, CHARLES DAVIDOFF, a citizen of the United States, residing at 705 Belmont Avenue, Brooklyn, in the county of Kings and State of New York, have invented certain new and useful Improvements in Watches, of which the following is a specification.

My invention relates to a new and improved form of watch.

One of the objects of my invention is to provide a new and improved form of watch, and particularly a new and improved form of wrist watch, in which the parts are so mounted and connected that the movement-bearing part can be readily separated from the case for inspection and repair.

Another object of my invention is to provide a new and improved form of wrist watch consisting of a case portion, a cover portion and a movement carrying or bearing portion which will be so connected that the device can be quickly and economically manufactured and can be easily inspected or repaired.

Another object of my invention is to provide a watch, and more particularly a wrist watch, of the type above specified which can be used in combination with a chain or a ribbon for holding it on the wrist of the wearer.

Another object of my invention is to provide a new and improved watch, and more particularly a wrist watch, in which the cover portion and the movement-bearing portion are urged away from the case portion by means of springs and are normally held in place by a suitable latch.

Other objects of my invention will be set forth in the following description and drawings which illustrate a preferred embodiment thereof.

Fig. 1 is a side elevation.

Fig. 2 is a top view.

Fig. 3 is a detail view partially in section.

Fig. 4 is a detail sectional view.

The watch has a case portion 2 having the shape shown in Fig. 3 and provided with lugs or brackets 4 having the shape shown in Fig. 2 and in Fig. 3. Said lugs or brackets 4 can be connected to the case portion 2 by any suitable method, such as soldering and the like.

The bracket portions 4 are preferably provided with hook-like and inwardly bent pro-

jections 4' for a purpose to be later described.

The cover portion 1 of the watch is provided with a suitable transparent glass or crystal top T, and it is provided with perforated ears 5 which are secured thereto by any suitable method, such as soldering. The movement carrying member 3 is also provided with similar perforated ears 5. The parts are so dimensioned that the ears 5 of the cover portion 1, for example, snugly fit against the brackets 4 provided at one end of the casing 2 so that the members 4 and 5 can be connected by means of a pintle 8 which is rigidly secured to the lugs 4 by hammering the ends of the said pintle 8 so as to enlarge them so as to give the effect of a rivet.

The pintle 8 is provided with a torsion spring 7 and one end thereof is bent over so as to firmly hold on to one of the brackets 4 before the said spring 7 is put under torsion.

After this is done and before the sleeve 6 is applied, the other end of the said spring 7 is secured to the opposite ear 5 and bent into position, as shown in Fig. 4 so that it remains in said position and the spring 7 is preferably placed under slight torsion when this is done so that the said spring 7 tends to force the cover 1 into the position shown in Fig. 3 and against the ends 4' which prevent the said cover part 1 from being moved backwards away from the vertical position.

A similar spring 7 mounted in a similar manner operates on the movement-carrying portion 3.

The movement-carrying portion fits directly into the case 2 but projects above the said case and it is provided with the ordinary crown C for winding the watch. The cover portion 1 is provided with a notch or recess so that it can fit snugly over the movement carrying portion and it is also provided at the outer end thereof with a spring latch 9 which snaps over the case 2 so as to firmly hold the parts in position. Of course by releasing the catch or latch 9 the parts are automatically moved into the position indicated in Fig. 3 so that all parts of the watch can be readily inspected and it is also easy to gain access to the movement for purposes of repair.

The springs 7 are covered by means of sleeves 6 which are applied after the before mentioned parts have been assembled. In

the embodiment shown herein the sleeves 6 are connected to a chain F but of course my invention is not limited to a watch which is used in connection with a chain as the watch 5 could be secured in position by means of a ribbon if desired, the said ribbon being suitably passed around the sleeves 6.

I have described a preferred embodiment 10 of my invention but it is clear that numerous changes and omissions could be made without departing from its spirit.

It is preferred to assemble the parts while 15 the movement-carrying portion, and the cover portion are in the vertical position, so that when the last mentioned parts are moved into the case 2, the springs 7 are placed under substantial torsion.

I claim:—

1. A watch comprising a case portion, 20 having two pairs of perforated external lugs secured thereto, a movement-carrying portion having a pair of perforated lugs adapted to be placed within one of the before mentioned pairs of lugs, a pintle passing through the adjacent lugs of the said case portion and of the said movement-carrying portion and adapted to movably

connect them; a torsion spring located on the said pintle and connected to the said case portion and to the said movement-carrying portion and adapted to urge the said movement-carrying portion away from the said case portion, said movement-carrying portion being adapted to fit into the said case portion, a cover portion having a pair of 35 perforated lugs adapted to be placed within the other of the before mentioned pairs of lugs, a pintle passing through the adjacent lugs of the case portion and of the said cover portion and adapted to movably connect 40 them, a torsion spring located on said pintle and connected to the said case portion and to the said cover portion adapted to urge the cover portion away from the case portion.

2. A device according to claim 1 in which 45 the perforated external lugs secured to the case portion have inwardly bent ends which are adapted to limit the movement of the movement-carrying portion and of the cover portion. 50

In testimony whereof I hereunto affix my signature.

CHARLES DAVIDOFF.
